United States Patent Office

Des. 179,300
Patented Nov. 27, 1956

179,300

TABLE

James E. Jones and Edward P. Stevens, Toledo, Ohio, assignors to The Hettrick Manufacturing Company, Toledo, Ohio, a corporation of Ohio

Application December 27, 1955, Serial No. 39,482

Term of patent 14 years

(Cl. D33—14)

FIG. 1.

FIG. 2.

Fig. 3.

Fig. 4.

Figure 3 is a perspective view on an enlarged scale, of the table, a portion being broken away, more clearly to illustrate the various elements; and

We claim:

The ornamental design for a table, as shown.
